UNITED STATES PATENT OFFICE.

WILLIAM S. HADAWAY, JR., OF NEW YORK, N. Y.

ELECTRIC RESISTER.

1,200,352.

Specification of Letters Patent.

Patented Oct. 3, 1916.

Application filed September 5, 1911. Serial No. 647,689.

To all whom it may concern:

Be it known that I, WILLIAM S. HADAWAY, Jr., a citizen of the United States, residing at New York, in the county of New York and State of New York, have invented new and useful Improvements in Electric Resistors, of which the following is a full, clear, concise, and exact description, reference being had to the accompanying drawing, forming a part of this specification.

This invention relates to electric resistors.

It particularly relates to resistors for use in electric heaters.

It has heretofore been proposed to use uninsulated wires for heating purposes, but the use of such wires has necessitated the provision of some separate means for insulating the wires in order that the same may not become grounded or cause damage. It has further been proposed to provide large heating units wherein a bare or insulated wire is inclosed in casings formed of several separate parts, but the use of such casings has unduly increased the cost of the heating means, and the form of the casing has interfered with the adaptation of such devices to a wide range of uses. Further, in both instances, above mentioned, the heat radiating efficiency of the heating means has not been at its maximum, the efficiency in the first instance being cut down by the insulating means, and in the second instance, by the inclosing casing.

My invention has among its objects to provide an improved electrical heating conductor, containing in itself all of the elements of a complete and efficient heating unit which may be made up into the form of a flexible conductor, in which the current carrying part is effectually insulated from the heat radiating part electrically, but is in direct heat conducting relation to the same.

My invention further has among its objects to provide an electric heating conductor which may be made up into any desired length, any portion of which forms a complete and efficient heater and one which may be used in any of the forms which a conductor may assume.

Other objects and advantages of my improved construction will hereinafter appear.

In accordance with a preferred form of my invention, I provide a conductor having a core of conducting material, which is incased in an insulating material having the

property of conducting the heat rapidly from the core, this material in turn being inclosed in a casing or sheath having the property of readily radiating the heat generated by the passage of the current through the core.

In the accompanying drawings, I have illustrated several forms which my invention may assume in practice.

In the views of these drawings: Figure 1 shows a central longitudinal sectional view of one form of my improved conductor. Fig. 2 shows a transverse section of the same. Fig. 3 shows a transverse section of my improved conductor made up into square form. Fig. 4 shows one form of my improved conductor applied to use in a resistance grid. Fig. 5 shows one form of the same, used as a pan-cake coil. Fig. 6 shows the same in helical form and used as a tool heater. Fig. 7 shows the same applied to use as a liquid heater. Fig. 8 shows the same embedded in a casting. Fig. 9 shows the same used in connection with a soldering iron.

In Fig. 1 I have illustrated a length of conductor comprising a core 1, surrounded by a coating of insulating material 2, which is, in turn, inclosed in a casing or sheath 3, all of said elements being concentrically arranged.

The core 1 is formed of a conducting material. In a preferred form I form this core of a high resistance material, such as nickel-chromium or copper-nickel, since I find that these alloys are well adapted to withstand high temperatures and readily radiate heat. Other resistance materials may, however, be used if desired.

The inclosing insulating coating 2 is preferably formed of a material which is adapted to readily absorb the heat generated by the passage of the current through the core 1, and transmit this heat to the radiating casing 3, at the same time effectually insulating the core from said casing. In a preferred form I may form this coating of a compound of equal parts of alumina and silica. However, other insulating material may be used.

The inclosing casing 3 is preferably formed of a material adapted to readily radiate the heat conveyed to it by the insulating material 2 from the core 1. Further, this casing is preferably formed of a material which is adapted to withstand high

temperatures without scaling. In a preferred form, this casing is formed of nickel-chromium or copper-nickel alloy, similar to the alloy used for the core, since I find that such alloys are well suited to this purpose. However, other materials having these properties may be used if desired.

In Fig. 2 my improved conductor has been shown made up into cylindrical form. 10 It may, however, be made up into the form shown in Fig. 3, wherein it has a square cross-section, since in this form it is adapted to provide a flat surface which permits it to come into more immediate contact with 15 the objects to be heated. In this form, if desired, the casing 3, may be rectangular in shape and inclose the insulating material 2, which has a corresponding shape. The core may obviously be formed with any desired cross-section. As illustrated in Figs. 20 1 and 2 the conductor may be made up into any desired length and thickness, and, if desired, may be made flexible, so that it may be bent into any desired shape; the 25 core insulating material and casing being so united with each other as to form a unitary structure, which will withstand the bending of the conductor into any desired form. Further, due to the use of my improved 30 combination, the metallic parts are brought into such intimate contact with the insulating material that the heat which is generated by the core is transmitted directly to the radiating casing by conduction and 35 with small loss. In a preferred form, the radiating casing or sheath is formed in one piece, and thus the conductor when complete is entirely unitary.

In Fig. 4, I have shown an application of 40 my improved conductor to a resistance grid, in which the ends of convolutions of the conductor are held between conducting or nonconducting strips 4, as in the usual construction. If desired, the ends of these 45 convolutions may be held in place by suitable pins 5. It is evident that the conductor may be fixed to these strips by any suitable means, and that the device may be used in any suitable relation, either as a resistance 50 unit or a heating unit, the conductor being entirely insulated electrically from any surface with which it comes in contact. For instance, this device may be used as a toaster, a grid or a grill, or may be placed within an oven to heat the same, or applied to any of a wide range of uses, as a heating means for any form of matter.

In Fig. 5, I have illustrated my improved conductor wound in the form of a pan-cake 60 coil. Obviously the conductor when wound in this form may be applied to any desired use, either as a heating element or as a resistance element, and may be placed in any desired relation with other heating devices.

65 In Fig. 6, I have shown my improved con-

ductor in the form of a helical coil, adapted to use as a tool heater. In this figure a tool has been diagrammatically shown at 6 in dotted lines. It is evident that any tool may be inserted within a coil of any suitable configuration and that the tool will be heated by the heat radiated from the sheath 70 3 of the conductor, which may be readily brought to any desired heat. For instance my improved conductor may be readily 75 adapted to use as a heater for curling irons.

In Fig. 7, I have shown my improved conductor used as a heating means for a liquid in which it is submerged. This liquid may be of any sort and contained in any 80 suitable receptacle. In this figure I have indicated the liquid at 7, contained in a receptacle 8. If desired a metal bath may be heated by simply immersing a few turns of the conductor within the same. It is to 85 be noted in this connection that the current carrying part of the conductor is effectually insulated from the bath and from the air, so that it is protected from the action of either; and, further, that the heat generated by the conductor and transmitted to the bath may be readily varied, by varying the number of turns of the conductor within 90 the in the bath.

In Fig. 8, I have illustrated my improved 95 conductor embedded in a metal plate 9. If desired, the conductor may be cast within any suitable metal having a melting point below that of the conductor sheath. In such a construction the conductor forms a 100 unitary part of the device, in which the elements of the heater which go to make up the conductor are amply protected. Further, the heat generated by the conductor, is directly conducted from the same by 105 means of the metal, and a very efficient heater is formed.

In Fig. 9 I have shown an adaptation of the construction shown in Fig. 8, in which the conductor is cast in the tip of a soldering iron 10. It is obvious that the conductor may be arranged in any desired form and disposed in any desired relation with respect to the surface of the iron. In a preferred form it is made up so that the 115 conductor is wound in convolutions in comparatively close proximity to the surface of the side of the iron but which are brought closer together at the tip, so that a greater heat is imparted to this portion.

120 It is of course understood that while in Figs. 4 and 9 inclusive, the conductor is shown as having a circular cross-section, the conductor may also be shaped so that it has a rectangular cross-section and applied to the various uses just described. When in this form, the conductor presents a substantially smooth surface to the article to be heated, and the heat is more evenly diffused. For instance, in the form shown 130

in Figs. 5 and 6 the convolutions may be placed so closely together that single smooth surface is presented to the article to be heated.

5 By the use of my improved construction I am able to provide an electric heating conductor of high efficiency, which may be made up into any desired shape and used in any desired relation. Further, any desired length of my improved conductor 10 forms a complete heating unit in itself, in which the parts of an efficient heating unit are so combined as to provide a unitary structure in which the conduction and radi- 15 ation of the heat is at a maximum, and the loss of heat during the passage of the same from the heating core is reduced to the minimum. Further, the radiating casing while in direct heat conducting relation to 20 the current carrying core, is effectually insulated from this core electrically so that the conductor may be laid wherever desired without the provision of current insulating means. Further, my improved conductor 25 may be made flexible, so that it may be readily bent or wound into various forms. Further, by the provision of my improved conductor I have made a single heating conductor which combines all the elements 30 of an efficient heater within itself and which may be adapted to use as a heating element for any device in the electrical heating field.

While I have in this application described specific forms which my invention may assume in practice, I do not wish to be limited 35 to these forms, but wish rather to include within the scope of this application all those forms of my invention falling within its spirit.

40 What I claim as new and desire to secure by Letters Patent is as follows:—

1. An electric resister comprising a resistance wire inclosed in a continuous tubu-

lar casing, said wire being insulated from said casing by a filling composed of a compound of alumina and silica, said wire and casing being flexible so that the resister may be bent to any suitable shape, said resister being adapted to be manufactured in comparatively long sections and thereafter severed into lengths which may be mounted or supported in any suitable manner regardless of the electrical conducting properties of the support. 45

2. An electric resister comprising a resistance wire incased in a continuous nickel chromium tubing, said wire being insulated from said tubing by a filling composed of a compound of alumina and silica, said wire and casing being flexible so that the resister 50 may be bent into any desired shape, said resister being adapted to be manufactured in comparatively long sections and thereafter severed into lengths as needed and mounted or supported in any suitable manner 55 regardless of the electrical conducting properties of the support. 60

3. A heating unit comprising a nickel-chromium wire, a continuous tubular casing of nickel-chromium and a filling of a compound alumina and silica, said wire and casing being flexible, whereby the unit may be bent as desired, said unit being adapted to be made up in stock, severed into lengths as needed and mounted or supported in any 70 suitable manner, regardless of the electrical conducting or non conducting properties of 75 said support.

In witness whereof, I have hereunto subscribed my name in the presence of two wit- 80 nesses.
